United States Patent Office.

S. J. THOMAS, OF DAWSON, GEORGIA.

Letters Patent No. 84,394, dated November 24, 1868.

IMPROVED WATER-WHEEL.

The Schedule referred to in these Letters Patent and making part of the same.

To all whom it may concern:

Be it known that I, S. J. THOMAS, of Dawson, in the county of Terrell, and State of Georgia, have invented a new and useful Improvement in Water-Wheels; and I do hereby declare that the following is a full, clear, and exact description thereof, which will enable others skilled in the art to make and use the same, reference being had to the accompanying drawing, forming part of this specification, which represents a perspective view of my invention.

This invention relates to a new and useful improvement in the buckets of water-wheels; and

It consists in constructing and arranging the buckets in such a manner that the best possible effect is obtained from the reactive force of the water.

A is the rim of the wheel, or a portion thereof, and B represents one of the buckets, which is inclined from a horizontal plane, and has its lower part curved down rather abruptly, as shown clearly in the drawing at a^X.

The position of the adjoining or successive bucket is shown by the red line in the drawing.

This form and position of the buckets admit of the ready discharge of the water, and at the same time the buckets receive a large percentage of the reactive force of the water.

The rim or segments A of the wheel are fitted together by a notched and lapped joint, a lip or projection, a, fitting in a recess, b, c fitting in d, and e fitting in f, as clearly shown in the drawing.

By this construction and arrangement, a very economical and efficient reaction water-wheel is obtained.

Having thus described my invention,

I claim as new, and desire to secure by Letters Patent—

The wheel, composed of sections or segments A, with buckets B, the segments joined by means of the projections a e c fitting into the recesses b f d, all constructed and arranged in the manner set forth.

S. J. THOMAS.
